CLAIM

The ornamental design for an electronic cigarette, as shown and described.

DESCRIPTION

FIG. 1 is a perspective view of the electronic cigarette showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the electronic cigarette where an electronic cigarette body is separate from an electronic cigarette cover;

FIG. 10 is an enlarged view of portion 10 of FIG. 1; and, FIG. 11 is a top plan view of the electronic cigarette of FIG. 7, shown enlarged for clarity of disclosure.

The evenly spaced broken lines depict portions of the electronic cigarette that form no part of the claimed design. The dash-dot broken lines encircling the enlarged detail view are for annotative purposes that form no part thereof.
